(57) **CLAIM**

The ornamental design for a tweezer, as shown and described.

DESCRIPTION

FIG. 1 is a perspective view of a tweezer showing our new design.

FIG. 2 is a front view thereof.

FIG. 3 is a back view thereof.

FIG. 4 is an enlarged left side view thereof.

FIG. 5 an enlarged right side view thereof.

FIG. 6 is a top view; and,

FIG. 7 is a bottom view thereof.

The broken lines in the figures are for the purpose of illustrating portions of the tweezer, which form no part of the claimed design.
